FASTENING-INSERTING MACHINE

John T. Lancaster, Newton, Mass., assignor to
United Shoe Machinery Corporation, Flemington, N. J., a corporation of New Jersey

Application October 4, 1940, Serial No. 359,751

34 Claims. (Cl. 1—32)

This invention relates to machines for inserting fastenings to secure together work-pieces, it being more particularly concerned with the attaching of heels to shoes, as by nails driven from within the shoes into the heels.

In machines of this character, the inserting force, which must be exerted upon the entire group of fasteners employed to effect attachment, may be so great as to require an excessive hold-down-pressure to retain the work against displacement upon its support. To avoid this, it has been proposed to divide the entire group necessary for each attachment into sets which are inserted successively. My invention has as an object the provision for this purpose of fastening-inserting means, which is both efficient and extremely simple. In the attainment of this object, I arrange to reciprocate, both within a frame and within a jack or work-support mounted on said frame, sets each made up of a plurality of flat plates situated side by side, the plates of each pair of the two sets being of similar form, vertically aligned and registering with each other. The respective pairs of plates are connected for positive movement together in opposite directions. The support-plates carry fastening-drivers, and the frame-plates are reciprocated, as by a plurality of cranks upon a driving shaft. Such an organization is compact, inexpensive to manufacture and so durable as to require little maintenance-expense. To permit the inserting design to be altered readily, the work-support is slidably mounted in ways upon the frame, and there is connecting means between the frame-plates and support-plates, which will separate when the support with its plates and drivers is to be changed.

It is a common practice, in connection with the supply of fastenings to inserting mechanisms of such machines as those for attaching heels, to deliver the fastenings to loading mechanism at one position and to transfer the load to the inserting mechanism at an operating position. Another object of this invention is to reduce the number of transfers of the fastenings, by eliminating the loading mechanism and making the delivery directly to the inserting mechanism. To this end, the shoe-support or jack, with its fastening-drivers, is movable under the power of the machine between the loading position, at which fastenings may be supplied to its drivers either by hand or automatically through tubes from a distributor, and the operating position, where there is means for actuating the drivers to insert the fastenings in the work. More specifically,

a slide is movable in the frame of the machine and carries the jack with its drivers. There is gearing which reciprocates the slide with the loaded jack, to bring the drivers into and out of operating relation to the means which actuates them. The gearing may be actuated through clutch mechanism controlled by the operator. When the drivers are arranged in the work-support in groups operated through sets of separable plates, mounted respectively in the frame and work-support as previously pointed out, the slide, in moving the support from the loading position into the operating position, causes connection between the sets of plates.

15 In heel-attaching or other fastening-inserting machines, the work must be held firmly upon its support to resist the driving forces, and it is customary to apply to said work preliminary or measuring pressure, which establishes contact 20 of the engaging elements with the work by their relative movement and permits a positioning of said work, thereafter final pressure being applied to clamp the work for the insertion of the fastenings. A further object of this invention is to cause, in a novel and effective manner and without delay, the application of full work-retaining force with no possibility of its diminution through slipping between force-transmitting elements. This result, I obtain by combining with 25 relatively movable work-pressure members, as fastening-inserting mechanism and heel-abutment mechanism, a member for causing the application of final pressure and an actuating member movable to operate the pressure member 30 and upon which said pressure member is movable, together with means for securing the pressure member against movement upon the actuating member to lock preliminary pressure upon the work. The pressure member may be rotatable during the application of preliminary pressure, and then positively secured against rotation 35 to effect the locking. Thereafter, its bodily movement may produce final pressure, which may be increased during insertion of the fastenings and 40 may be limited in magnitude. The preliminary pressure is preferably created by the operator, while the final pressure is under the power of the machine and governed by the operator. To give this control, the actuating member is power-driven, and there is a latch by which said actuating member is held in inactive relation, to be 45 released by means through which the operator governs the power means. The release of the actuating member gives the locking effect for the preliminary pressure previously referred to, and 50 55

unfailingly holds this upon the work, it being applied without the loss of time which would be introduced were the lock to be produced during the power-cycle of the machine. I have shown the final pressure as created by gearing, preferably of spiral form having an element arranged for compound movement, which may be made up of bodily and rotary components. Idle movement of this element in one direction, as its rotation, will permit the application of the preliminary pressure by the operator, while the second or bodily movement may produce the final pressure under the power of the machine. The driven element of the gearing is upon a spindle having a screw threaded into a nut upon the heel-abutment and movable against the resistance of a spring. The element having the compound movement is under the influence of the actuating member. It is free to rotate upon, said actuating member, while the other gearing element is being turned during the travel of the heel-abutment for the application of preliminary pressure, and is thereafter clutched to said actuating member, as a consequence of the movement thereof. The actuating member is preferably latched to maintain the clutch out of engagement during the creation of preliminary pressure, this latch being released when the operator causes the rotation of the power means, as a cam which applies final pressure.

In the accompanying drawings, in which is illustrated one form of the invention,

Fig. 1 shows my improved fastening-inserting machine in broken side elevation;

Fig. 2 is an irregular vertical transverse section;

Fig. 3, a broken front elevation of the work-support and abutment mechanism; and

Fig. 4, an enlarged horizontal section on the line IV—IV of Fig. 3.

The machine-frame is preferably in the form of a column 10, at the front of which rises from a bracket 12 a post 14, which may be considered as a portion of the frame. At its top, the post is tied to the body of the frame by a horizontal brace 16, which extends back into the interior of the column. In the brace are horizontal ways 18, in which a base 20 of a jack or work-support 22 is mounted to slide. This jack is movable, in a manner to be later described, between a forward operating position, as it appears in the drawings, and a rearward receiving position beneath a foot-plate 24. Through the foot-plate, with its connected tubes 26, nails or other fastenings are supplied from an unillustrated distributor. In the jack are vertical passages 28 arranged in accordance with a particular nailing design, and in these passages nail-drivers are movable. The forward or breast-drivers 30, 30 and the next or intermediate drivers 32, 32 rise in pairs from vertically-extending plates 34 and 36, respectively, while the fifth or rear driver 38 is carried by a plate 40. Each of the driver-plates is separably latched in the jack by a spring-actuated pin 42, guided in the jack-body and entering a vertically elongated depression in the corresponding plate. When the jack is removed from its ways for the substitution of another having its drivers arranged according to a different design, the latch-pins prevent the accidental separation of the plates and drivers from the jack, yet permit them to be removed for driver-adjustment or for the replacement of broken drivers. The separable retention of the jack is effected by a spring-actuated latch 44, mov-

able in the lower portion of the jack and engaging its actuating slide 46. The jack-plates 34, 36 and 40 are guided for vertical movement side by side in a cavity in the jack, as may be best seen in Fig. 4 of the drawings. In the lower edge of each plate is a recess 50, shown as T-shaped (Fig. 3), this receiving a complementally formed projection 52 at the top of the corresponding one of three plates 54, 56 and 58 guided in the frame-post 14 in a manner similar to the respective plates 34, 36 and 40 and of like form. These lower driver-actuating plates have connections by which they are moved positively in opposite directions, as they also move the respective upper driver-carrying plates with which they are vertically aligned. Springs for the retraction of the drivers are therefore unnecessary. Each connection may consist of a circular projection 60 from the bottom of one of the actuating plates, this being surrounded by a complemental depression 62 in a connecting rod 64. Each connecting rod is operated by one of a set of three cranks 66, 68 and 70, separated from one another by 120° about a driving shaft 72. This shaft is journaled horizontally in the lower portion of the column 10, and receives power constantly, while the machine is in use, through gearing 74 and clutch mechanism indicated at 76 (Fig. 1). The initial heights of the drivers 30 are such that, as the spaced cranks are turned through one revolution in the direction of the arrow in Fig. 3, the drivers 30 are first lifted through the pair of plates 54 and 34 to insert in the jacked work the nails which they carry. After these nails have been fully driven, the drivers 32 act, followed by the drivers 38. As a result of this progressive insertion, the force necessary to resist the displacement of the work from the jack 22 is never more than that which will adequately oppose the driving of two nails. Obviously, the number and manner of grouping of the sets of plates and drivers may be altered, as is found convenient.

The jack-base 20 has extending rearwardly from it the slide 46, previously referred to, this being guided in the brace 16 and having upon its upper face rack-teeth 80. With these teeth meshes a gear 82 fast upon a sleeve 84, rotatable about a shaft 86 journaled horizontally in the column 10. This shaft is driven from the constantly rotating shaft 72 through gearing 87, portions of which appear in Figs. 1 and 2. At the outer extremity of the sleeve a pinion 88 is secured, and has meshing with it a gear-segment 90 mounted to oscillate about a spindle 92 projecting horizontally from the column. The outer side of the segment has a projection 94 entering a cam-groove 96 in a disk 98 surrounding the shaft 86. The disk may be rotated from the shaft through clutch mechanism C contained within a casing 100 forming a part of a hand-lever 102, fulcrumed at 104 upon the frame-column and arranged for manipulation by the operator. The hand-lever is held normally raised, with the clutch disconnected, by a tension-spring 105. The type of clutch employed is not important, one which is suitable being that disclosed in Letters Patent of the United States No. 2,214,835, Lancaster, September 17, 1940. Depression of the lever 102 and consequent engagement of the clutch will cause a single rotation of the disk 98. This, through the sleeve 84, gear 82 and rack 80, will produce a complete reciprocation of the jack-slide 46 to carry the jack 22 from its operating position, as seen in

Fig. 1, to a point beneath the foot-plate 24 to receive a load of nails and back to operating position. In its travel, the connecting means 50 and 52, between the jack-plates 34, 36 and 40 and the frame-plates 54, 56 and 58 by which they are actuated, are separated, the depressions in the jack-plates remaining in horizontal registration with the projections of the frame-plates supported upon the latch-pins 42. Upon the return of the jack-plates to their normal positions, the depressions again surround the projections, ready for operation.

To cause the delivery of nails through the tubes 26 and foot-plate 24 to the jack when it is in the rearward position, a reciprocating picker-plate or oscillatory picker-disks, which remove nails in successive loads from the raceways of a distributor, for example as in Letters Patent of the United States No. 1,867,560, Benjamin, July 19, 1932, may be controlled in their operation in opposite directions from the cam-disk 98. For this purpose, the disk has a peripheral cam-surface 106 with which contacts a roll 108, rotatable upon one arm of a bell-crank-lever 110, fulcrumed upon the spindle 92. The roll is held against the cam-surface by a tension-spring 112 and, as the disk rotates, connection of the lever 110 to the distributor by a rod 114 will cause the actuation of the picker-plate or disks in one direction to tension a spring, and thereafter release the picker-device or devices to permit them, under the influence of the spring, to deliver a load of nails from the raceways. The separation of the nails will occur during the rearward travel of the jack, they dropping through the tubes and foot-plate into the passages 28, as said jack waits to receive them.

Situated above the jack 22 is a holdown or heel-abutment mechanism A, which may be conventional in form. It is mounted upon a slide 120 guided for vertical movement at the front of the column 10, and held normally elevated from the jack by a tension-spring 122 extending between the bottom of the column and a lever 124, fulcrumed within the column and pivoted to the slide. To bring the abutment A into preliminary engagement with a heel to be attached, the lower portion of the slide 120 is joined by a rod 126 to a treadle 128, fulcrumed yieldably at 130 near the bottom of the column. After the holdown engages the heel, the treadle turns about its connection 132 to the rod 126, and its initial fulcrum 130 rises to trip the clutch mechanism 76 through a link 134, which turns a spindle 135 carrying a stop-arm 136 of the clutch. This starts the power-cycle of the machine. Fixed upon the lower portion of the slide 120 is a nut 138, through which is threaded a screw 140 formed upon a vertical spindle 142 rotatable within a casing 144, secured at 146 inside the column. The spindle turns within a bushing 148 threaded into the top of the casing, and fast upon its lower extremity is a spiral gear 150 normally resting upon a step-bearing 151 at the bottom of the casing. Between the gear and a thrust-bearing 152 at the lower end of the bushing, a compression spring 154 is interposed. By varying the vertical position of the bushing, the resistance of the spring to compression may be altered. Guided for vertical reciprocation in one side of the casing is an actuating rod 156, splined at 158 to prevent rotation. Secured to the rod is a collar 160, and resting upon this is a spiral pinion 162 meshing with the spiral gear 150 and normally free for rotation thereby about the rod. The pinion, also being

shiftable bodily with the rod, thus has a compound movement of rotation and translation. Upon the upper end of the pinion and the lower end of a collar 164 fast upon the actuating rod 156 are co-operating clutch-teeth 166, 168, respectively. The rod is held normally raised to separate the teeth 168 from the teeth 166 by a latch-arm 170, free to turn upon the spindle 135, in an angular recess at the upper extremity of which the lower end of the actuating rod rests. The rod and arm are drawn yieldably together, tending to produce entrance of the rod into the arm-recess, by a tension-spring 172, which connects the bottom of the rod to a projection 174 from the latch-arm. When the clutch mechanism 76 is tripped by a counterclockwise rotation of the spindle 135 (Fig. 2) produced by the treadle 128, a projection 176 extending horizontally from an arm 178 fixed to the spindle 135, forces the latch-arm 170 from beneath the rod, leaving this free to be drawn down by the spring 172. There is thus produced the engagement of the clutch-teeth 168 and 166. During the preliminary pressure-movement of the slide 120 under the influence of the treadle to bring about engagement of the abutment A with a heel, the nut 138 rotates the screw 140, this turning the gear 150 upon the spindle 142. Rotation of the gear is not interfered with by the meshing pinion 162, since this is free to turn about the actuating rod 156 because of disengagement of the clutch-teeth. Continued depression of the treadle turns the stop-arm 136 to cause the clutch mechanism 76 to rotate the shaft 72, initiating a power-cycle of the machine. Fast upon the shaft is a disk 180 in the side of which is a cam-groove 182. Lying in the groove is a roll 184, rotatable upon a lever 186 fulcrumed at 188 upon the column 10. The free end 190 of the lever lies in a recess near the bottom of the rod 156. In the normal position of the disk, the roll 184 is situated opposite a depression 192 at the inner side of the cam-groove 182. Therefore, when the treadle-depression first shifts the arm 170 to unlatch the rod 156, the roll is free to enter the depression, and the descending end 190 of the lever 186, before the clutch mechanism 76 is tripped, will allow the spring 172 to draw down the rod abruptly to engage the clutch-teeth 168 and 166, securing the pinion 162 to the rod. This is followed by the engagement of the clutch 76 and the rotation of the shaft 72 under the power of the machine, causing the cam-groove 182 in the new rotating disk 180 to lower positively the end 190 of the lever 186. This draws down the rod and the locked pinion, and spiral teeth of the latter, acting upon the like teeth of the gear 150, will force these to one side, rotating the spindle 142 and the screw 140. The nut 138 is thereby caused to descend, lowering the slide 120 so the abutment A applies final clamping pressure to the work. The magnitude of this pressure may be variably determined by turning the bushing 148 to change the resistance of the spring 154 to compression. When, in this pressure-movement, the spring yields, the force applied to the work by the abutment A is through said spring, which, as it is compressed, offers a gradually increasing resistance. This correspondingly increases the hold-down pressure, so, as the fastenings are driven farther into the work, it is more effectively retained upon the jack. At the same time, the ultimate pressure is so limited that the heel will not be crushed. As the cam-depression 192 approaches the roll 184 at the termination of the

operating cycle, the cam-groove 182 lifts the end 190 of the lever 186, so the actuating rod 156 is elevated until its lower extremity may be drawn by the spring 172 into the recess in the arm 170. The clutch-teeth 168 are now latched in their disengaged relation; the disk 180 stops with its cam-depression 192 opposite the lever-roll 184; and the screw 140 is freed for rotation by the nut 138 during the succeeding application of preliminary pressure to the work. The extent to 10 which hold-down-pressure is placed upon the work as the driving of the fastenings progresses may be determined, not only by the resistance of the spring 154, but also by the contour of the cam-groove 182. By the latter, for example, the work-retaining force may be increased just as the heads are being sunk in the insole.

In using the machine, there being a jack 22 with its driver-passages 28 arranged in the desired nailing design latched at 44 to its actuating 20 slide 46, the operator depresses the lever 102 to cause the connection of the cam-disk 98 to the constantly driven shaft 86 by the clutch mechanism C. The cam-groove 96 of the disk, acting through the gearing 88, 82, 80, carries the slide rapidly back until it approaches its nail-receiving position beneath the foot-plate 24, slows it as it approaches the termination of its travel, and holds it temporarily at rest with its passages 28 in registration with those of the foot-plate. At this time, the cam-surface 106 of the disk 98, acting through the rod 114, causes the delivery of a load of nails N from the distributor, these being deposited, points up, in the jack-passages upon the upper ends of the contained drivers. Then, the cam-groove 96 causes the return of the jack, first rapidly and then at a reduced rate, to its initial position beneath the abutment A, it being there maintained by the cam-groove, the rotation of the disk 98 having 40 been stopped by the disengagement of the clutch C. In the rearward movement of the jack, the depressions 50 in its plates leave the projections 52 upon the frame-plates, but again come into co-operation with them upon return to the forward operating position. It is to be observed that this loading of the jack with nails is accomplished by direct delivery to it, without the complication and uncertainty produced by interposed loading mechanism.

The operator places a shoe S upon the jack 22, locates a heel H upon the heel-seat and depresses the treadle 128. This turns about its fulcrum 130, and through the rod 126 draws down the slide 120 until the abutment A engages the heel. Since the clutch-teeth 168 and 166 are now separated, the rod 156 carrying the former is being latched up at 170, the spiral pinion 162 is free to turn idly, as is the meshing gear 150 and its spindle 142. The nut 138 upon the descending slide, therefore rotates the screw 140 without effect upon the slide. When contact of the abutment with the heel has been established and the work properly positioned upon the jack, the continued downward movement of the treadle 65 transfers its fulcrum to the pivot 132 upon the rod 126. Through the link 134, the spindle 135 is turned to at once free the rod 156 from the latch-arm 170. The spring 172 draws down the clutch-teeth 168 into engagement with the teeth 166, securing the pinion 162 against rotation 70 upon the rod. The spindle 142, with its screw 140 and gear 150, being thus held against rotation, the abutment A is positively locked in its preliminary pressure-supplying relation, before the 75

power operation of the machine starts and without the possibility of accidental retraction. Immediately following this, the further rotation of the spindle 135 with the stop-arm 136 frees the clutch mechanism 76 for engagement; the shaft 72 is rotated; and the power-cycle of the machine is initiated. The cam-groove 182 in the disk 180 causes the lever 186 to draw down the rod 156; and the now locked pinion 162 acts upon the gear 150 and through the inclination of the intermeshing teeth rotates the spindle 142 with its screw 140 to apply clamping pressure in a manner and to an extent determined by the resistance of the spring 154. With the work thus firmly held against upward displacement, the rotation of the cranks 66, 68 and 70 produces the successive reciprocation of the frame-plates 54, 56 and 58 and the connected jack-plates 34, 36, 40 positively in both directions. The sets of drivers 30, 32 and 38, therefore rise to insert the sets of nails N which they carry through the insole of the shoe S into the heel H, and are restored to their initial positions when disengagement of the clutch mechanism 76 stops the rotation of the shaft 72. Because preliminary pressure is locked upon the work by the clutch-teeth 166, 168 before the power-cycle of the machine begins, there need be no clearance between the insole of the shoe and the points of the nails upon the first-actuated drivers, giving a substantial saving of time. As the rotation of the disk 180 terminates, the cam-groove 182 elevates the rod 156 sufficiently for the spring 172 and arm 170 to latch up the said rod. The clutch-teeth 35 168 are separated from the teeth 166, so the gearing 162, 150 and the spindle 142 with its screw are free to rotate. The slide 120 is therefore released and is raised by its spring 122 to separate the abutment A from the jack. All the 40 elements of the machine are now in their normal positions, and, upon removal of the heeled shoe from the jack, it is ready for the succeeding operation. If the nailing design is to be changed, the operator, releasing the latch 44, pulls out the jack from its ways 18, the contained plates and drivers being retained within said jack by the latches 42. When the jack to be substituted is inserted in the ways, the latches for its plates locate the plate-depressions 50 in their correct relation to receive the projections 50 52 of the frame-plates. The latch 44 secures the jack to the slide 46, with this connecting means 50, 52 engaged in proper vertical registration.

Having described my invention, what I claim as new and desire to secure by Letters Patent of the United States is:

1. In a fastening-inserting machine, a frame, a work-support mounted thereon, a plurality of flat plates reciprocable side by side in the frame, a corresponding number of flat plates reciprocable in the work-support, the frame-plates and support-plates being arranged in vertically aligned pairs of similar form and registering with each other, fastening-drivers carried by the support-plates, and means for reciprocating the frame-plates.

2. In a fastening-inserting machine, a frame, a work-support mounted thereon, a plurality of flat plates reciprocable side by side in the frame, a corresponding number of flat plates reciprocable in the work-support and connected to the respective frame-plates in pairs the plates of which are coupled by the connection for positive movement together in opposite directions, fas-

tening-drivers carried by the support-plates, a driving shaft rotatable in the frame and having a plurality of cranks, and connecting rods joining the cranks to the respective frame-plates.

3. In a fastening-inserting machine, a frame, a work-support movable thereon, a plurality of flat plates reciprocable side by side in the frame, a corresponding number of flat plates reciprocable in the work-support, means connecting the frame-plates and support-plates and arranged to separate as the support is moved upon the frame, fastening-drivers carried by the support-plates, and means for reciprocating the frame-plates.

4. In a fastening-inserting machine, a frame, a work-support slidably mounted in ways thereon, a plurality of flat plates reciprocable side by side in the frame, a corresponding number of flat plates reciprocable in the work-support, means connecting the frame-plates and support-plates and arranged to separate as the support is slid in its ways, fastening-drivers carried by the support-plates, means for reciprocating the frame-plates, and means for separably securing the support in its ways with the connecting means of the respective pairs of frame-plates and support-plates in engagement.

5. In a fastening-inserting machine, a frame, a work-support slidably mounted in ways thereon, a plurality of flat plates reciprocable side by side in the frame, a corresponding number of flat plates reciprocable in the work-support, means connecting the frame-plates and support-plates and arranged to separate as the support is slid in its ways, fastening-drivers carried by the support-plates, means for reciprocating the frame-plates, and means for removably latching the support-plates to the support.

6. In a heel-attaching machine, a frame, a jack mounted upon the frame, a driving shaft journaled in the frame and having a plurality of cranks, a plurality of flat plates guided side by side in the frame, a plurality of flat plates guided side by side in the jack and being respectively aligned with the frame-plates, fastening-drivers carried by the jack-plates, and connecting rods joining the cranks to the frame-plates.

7. In a heel-attaching machine, a frame, a jack mounted upon the frame, a driving shaft journaled in the frame and having a plurality of cranks, a plurality of flat plates guided side by side in the post, a plurality of flat plates guided side by side in the jack and being respectively aligned with the frame-plates, there being means connecting the two sets of plates adapted to transmit between them movement in opposite directions, fastening-drivers carried by the jack-plates, and connecting rods joining the cranks to the frame-plates.

8. In a heel-attaching machine, a frame provided with a post, a jack separably mounted upon the post, a driving shaft journaled in the frame and having formed therein a plurality of cranks, a plurality of flat plates guided side by side in the post, a plurality of flat plates guided side by side in the jack and being respectively aligned with the post-plates, there being means separably connecting the post- and jack-plates and adapted to transmit between them movement in opposite directions, fastening-drivers carried by the jack-plates, and connecting rods joining the cranks to the post-plates.

9. In a heel-attaching machine, a shoe-support, fastening-drivers movable in the support, means situated at an operating position for ac-

tuating the drivers, means situated at a loading position for supplying fastenings to the support, and means operating under the power of the machine for presenting the support alternately at the loading and operating positions.

10. In a heel-attaching machine, a frame, a slide movable upon the frame, a jack movable by the slide and containing fastening-drivers, actuating means for the drivers, tubes through which fastenings may be supplied, and gearing for reciprocating the slide to present the jack to the fastening-supplying tubes and to the driver-actuating means.

11. In a heel-attaching machine, a frame, a rack slidable horizontally in the frame, a jack connected to the rack and containing fastening-drivers, actuating means for the drivers, tubes through which fastenings may be supplied, a gear meshing with the rack to shift the jack between the driver-actuating means and the fastening-tubes, and clutch mechanism through which the gear is driven.

12. In a heel-attaching machine, a shoe-support, fastening-drivers movable in separate sets in the support, an actuating member individual to each set of drivers and situated at an operating position, means situated at a loading position for supplying fastenings to the support, and means operating under the power of the machine for presenting the support alternately at the loading and operating positions.

13. In a heel-attaching machine, a frame, a slide movable upon the frame, a jack movable by the slide and containing a plurality of plates movable side by side and having fastening-drivers, a corresponding number of plates movable side by side in the frame, there being separable means for connecting one group of plates to the other, a foot-plate through which fastenings are supplied, and gearing for reciprocating the slide to present the jack to the foot-plate and to cause the separable means to connect the groups of plates.

14. In a fastening-inserting machine, fastening-inserting mechanism and work-abutment mechanism co-operating therewith, said mechanisms being relatively movable to produce preliminary and final pressure upon the work, a member for causing the application of final pressure, an actuating member movable to operate the pressure member, and upon which said pressure member is movable, and means for securing the pressure member against movement upon the actuating member to lock preliminary pressure on the work.

15. In a fastening-inserting machine, fastening-inserting mechanism and work-abutment mechanism co-operating therewith, said mechanisms being relatively movable to produce preliminary and final pressure upon the work, a member for causing the application of final pressure, an actuating member movable to operate the pressure member, and upon which said pressure member is movable, means for securing the pressure member against movement upon the actuating member to lock preliminary pressure on the work, and means for gradually varying the final pressure applied by the pressure member to the work.

16. In a fastening-inserting machine, fastening-inserting mechanism and work-abutment mechanism co-operating therewith, said mechanisms being relatively movable to produce preliminary and final pressure upon the work, a member for causing the application of final pres-

sure, an actuating member movable to operate the pressure member and upon which said pressure member is movable, means for securing the pressure member against movement upon the actuating member to lock preliminary pressure on the work, and means for limiting the degree of final pressure which may be applied by the pressure member to the work.

17. In a fastening-inserting machine, fastening-inserting mechanism and work-abutment mechanism co-operating therewith, said mechanisms being relatively movable to produce preliminary and final pressure upon the work, a member free to rotate during the application of preliminary pressure and bodily movable to cause the application of final pressure, and means for positively securing the pressure member against rotation to lock preliminary pressure upon the work and for producing bodily movement of the pressure member.

18. In a fastening-inserting machine, fastening-inserting mechanism and work-abutment mechanism co-operating therewith, said mechanisms being relatively movable to produce preliminary and final pressure upon the work, a member free to rotate during the application of preliminary pressure and bodily movable to cause the application of final pressure, means for positively securing the pressure member against rotation to lock preliminary pressure upon the work and for producing bodily movement of the pressure member, and means for gradually varying the final pressure produced by such bodily movement.

19. In a fastening-inserting machine, fastening-inserting mechanism and work-abutment mechanism co-operating therewith, said mechanisms being relatively movable to produce preliminary and final pressure upon the work, a member free to rotate during the application of preliminary pressure and bodily movable to cause the application of final pressure, means for positively securing the pressure member against rotation to lock preliminary pressure upon the work and for producing bodily movement of the pressure member, and means for limiting the final pressure produced by such bodily movement.

20. In a fastening-inserting machine, fastening-inserting mechanism and work-abutment mechanism co-operating therewith, said mechanisms being relatively movable to produce preliminary and final pressure upon the work, a member for causing the application of final pressure, an actuating member movable under the power of the machine to operate the pressure member and upon which said pressure member is movable during the application of preliminary pressure, and means for securing the pressure member against movement upon the actuating member to lock preliminary pressure on the work.

21. In a fastening-inserting machine, fastening-inserting mechanism and work-abutment mechanism co-operating therewith, said mechanisms being relatively movable to produce preliminary and final pressure upon the work, a member for causing the application of final pressure, an actuating member movable relatively to the pressure member to operate said pressure member, driving means by which the actuating member is moved, a latch by which the actuating member may be held in inactive relation to the driving means, and a member movable by the operator for first applying the preliminary pressure to the work and thereafter governing the

driving means and releasing the latch to effect the application of final pressure.

22. In a fastening-inserting machine, fastening-inserting mechanism and work-abutment mechanism co-operating therewith, said mechanisms being relatively movable to produce preliminary and final pressure upon the work, operator-controlled means for creating the final pressure, and gearing through which final pressure is applied, said gearing having an element arranged for compound movement, movement of said element in one direction permitting the application of preliminary pressure by the operator and movement of the element in another direction producing final pressure.

23. In a fastening-inserting machine, fastening-inserting mechanism and work-abutment mechanism co-operating therewith, said mechanisms being relatively movable to produce preliminary and final pressure upon the work, operator-controlled means for creating the final pressure, gearing through which final pressure is applied, and means for securing an element of the gearing against rotation to lock preliminary pressure upon the work.

24. In a fastening-inserting machine, fastening-inserting mechanism and work-abutment mechanism co-operating therewith, said mechanisms being relatively movable to produce preliminary and final pressure upon the work, operator-controlled means for creating the final pressure, gearing through which final pressure is applied, means for securing an element of the gearing against rotation to lock preliminary pressure upon the work, and means for transmitting to said work gradually increasing final pressure.

25. In a fastening-inserting machine, fastening-inserting mechanism and work-abutment mechanism co-operating therewith, said mechanisms being relatively movable to produce preliminary and final pressure upon the work, operator-controlled means for creating the preliminary pressure, gearing through which final pressure is applied, said gearing having an element arranged for compound movement, movement of said element in one direction permitting application of preliminary pressure by the operator and movement of the element in another direction producing final pressure, and means for limiting the degree of final pressure.

26. In a fastening-inserting machine, fastening-inserting mechanism and work-abutment mechanism co-operating therewith, said mechanisms being relatively movable to produce preliminary and final pressure upon the work, operator-controlled means for creating the final pressure, gearing through which final pressure is applied, means for securing an element of the gearing against rotation to lock preliminary pressure upon the work, and means for moving such element bodily to produce final pressure.

27. In a heel-attaching machine, nail-driving mechanism, a movable heel-abutment co-operating therewith, a rotatable screw having threaded connection to the abutment, an actuating member movable adjacent the screw, a spiral gear secured to the screw, a second spiral gear meshing with the first and being normally free to rotate upon the actuating member, and means for clutching the second gear against rotation upon the actuating member.

28. In a heel-attaching machine, nail-driving mechanism, a movable heel-abutment co-operating therewith, a rotatable screw having threaded connection to the abutment, an actuating mem-

ber movable adjacent the screw, a spiral gear secured to the screw, a second spiral gear meshing with the first and being normally free to rotate upon the actuating member, means for clutching the second gear against rotation upon the actuating member to cause the rotation of the screw as the actuating member is moved, and a spring against which the screw may yield.

29. In a heel-attaching machine, nail-driving mechanism, a movable heel-abutment co-operating therewith, a rotatable screw having threaded connection to the abutment, an actuating member movable adjacent the screw, a spiral gear secured to the screw, a second spiral gear meshing with the first and being normally free to rotate upon the actuating member, co-operating clutch members upon the actuating member and the second gear, and means for moving the actuating member to cause the engagement of the clutch members.

30. In a heel-attaching machine, nail-driving mechanism, a movable heel-abutment co-operating therewith, a rotatable screw having threaded connection to the abutment, an actuating member movable adjacent the screw, a spiral gear secured to the screw, a second spiral gear meshing with the first and being normally free to rotate upon the actuating member, means for clutching the second gear against rotation upon the actuating member, and a rotatable cam for moving the actuating member to cause the clutched gear to turn the companion gear.

31. In a heel-attaching machine, nail-driving mechanism, a movable heel-abutment co-operating therewith, a rotatable screw having threaded connection to the abutment, an actuating member movable adjacent the screw, a spiral gear secured to the screw, a second spiral gear meshing with the first and being normally free to rotate upon the actuating member, means for clutching the second gear against rotation upon the actuating member, a rotatable cam for moving the actuating member to cause the clutched gear to turn the companion gear, a latch by which normal disengagement of the clutch members is maintained, and means movable by the operator to cause the release of the latch and the rotation of the cam.

32. In a heel-attaching machine, nail-driving mechanism, a movable heel-abutment co-operating therewith, a rotatable screw having threaded connection to the abutment, an actuating member movable adjacent the screw, a spiral gear secured to the screw, a second spiral gear meshing with the first and being normally free to

rotate upon the actuating member, means for clutching the second gear against rotation upon the actuating member, a rotatable cam for moving the actuating member to cause the clutched gear to turn the companion gear, a latch by which normal disengagement of the clutch members is maintained, and means movable by the operator to cause the release of the latch and the rotation of the cam, the cam being provided

5 10 15 20 25 30 35 40 45 50

with means whereby the release of the latch occurs before rotation of the cam begins.

33. In a heel-attaching machine, nail-driving mechanism, a movable heel-abutment co-operating therewith, a rotatable screw having threaded connection to the abutment, an actuating member movable adjacent the screw, a spiral gear secured to the screw, a second spiral gear meshing with the first and being normally free to rotate upon the actuating member, means for clutching the second gear against rotation upon the actuating member, a rotatable cam provided with an operating surface in which is a depression, a lever having a portion arranged to enter the depression when the cam is in its normal position and connected to the actuating member, a latch for the actuating member by which the second gear is normally held inactive, and means for unlatching the actuating member to permit the lever-portion to enter the cam-depression and to effect the clutching of the second gear to the actuating member.

34. In a heel-attaching machine, nail- driving mechanism, a movable heel-abutment co-operating therewith, a rotatable screw having threaded connection to the abutment, an actuating member movable adjacent the screw, a spiral gear secured to the screw, a second spiral gear meshing with the first and being normally free to rotate upon the actuating member, means for clutching the second gear against rotation upon the actuating member, a rotatable cam provided with an operating surface in which is a depression, a lever having a portion arranged to enter the depression when the cam is in its normal position and connected to the actuating member, a latch for the actuating member by which the second gear is normally held inactive, means for unlatching the actuating member to permit the lever-portion to enter the cam-depression and to effect the clutching of the second gear to the actuating member, and a member movable by the operator to cause the release of the latch and the rotation of the cam.

JOHN T. LANCASTER.
